CLAIM

The ornamental design for a beverage container, as shown and described.

DESCRIPTION

FIG. 1 is a top, front perspective view of a beverage container, shown in environmental use, showing our new design;

FIG. 2 is a top, rear perspective view thereof;

FIG. 3 is a back view thereof;

FIG. 4 is a front view thereof;

FIG. 5 is a left side view thereof;

FIG. 6 is a right side view thereof;

FIG. 7 is a top view thereof;

FIG. 8 is a bottom view thereof;

FIG. 9 is a back view thereof, shown with the lid removed for clarity of disclosure;

FIG. 10 is a front view thereof, shown with the lid removed for clarity of disclosure;

FIG. 11 is a left side view thereof, shown with the lid removed for clarity of disclosure;

FIG. 12 is a right side view thereof, shown with the lid removed for clarity of disclosure; and,

FIG. 13 is a top view thereof, shown with the lid removed for clarity of disclosure.

The broken lines in the figures illustrate the portions of the beverage container and form no part of the claimed design. The broken lines showing the hand is for the purpose of illustrating environmental subject matter that forms no part of the claimed design.

1 Claim, 10 Drawing Sheets
